UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK.

SIGNAL SYSTEM.

Application filed May 16, 1924. Serial No. 713,694.

My invention relates broadly to signaling, and more particularly to a multiplex duplex transmission and receiving system for radio communication.

- 5 One of the objects of my invention is to provide a multiplex system of radio communication which may employ one radiating structure or antenna for a plurality of duplex radio communication systems.
- 10 Another object of my invention is to provide circuit arrangements in a multiplex system in which the several channels are provided with means for reducing interference from the local transmitting energy in 15 the same channel or associated channels connected to the same antenna.

Still another object of my invention is to provide a multiplex transmission system for operation on the same antenna having means 20 connected in the several channels for preventing or reducing reaction of the separate transmitting channels upon each other while enabling efficient radiation of signals from the same antenna without mutual interference.

25 Still another object of my invention is to provide selective circuit arrangements in the receiving channels of a two-way multiplex system eliminating undesired interference from the transmitting energy in the same channel or from sources of energy in adjacent channels, at the same time usefully employing a portion of the transmitting energy at the same station for operation 30 with incoming signaling energy to produce oscillations of intermediate frequency differing from other beat frequency oscillations which may occur in the system, which oscillations may be selected, detected, and 35 caused to reproduce the incoming signals without interference from cross-talk or from oscillations occurring simultaneously 40 at other points in the system.

The invention will be more clearly understood by reference to the following specification and the accompanying drawings, in which:

45 Fig. 1 represents a circuit arrangement for a multiplex transmitting circuit; and 50 Fig. 2 shows a circuit arrangement for a plurality of two-way multiplex channels operating in connection with the same antenna.

Heretofore in the art difficulty has been experienced in the operation of radio transmission and receiving systems closely adjacent each other by reason of cross-talk disturbances and mutual interference by reaction of one system upon the other. In installations on shipboard it has been necessary to provide separate antennæ for each channel of communication and substantially 55 separate the channels on widely different wave lengths, and even in such installations it has been very difficult to avoid reaction of 60 one system upon the other.

In the present invention I provide a multiplex radio communication system in which the several channels operate upon the same antenna system with means interposed in 65 each of the channels for reducing reaction of one system upon the other, enabling communications to be carried on simultaneously 70 utilizing the same antenna system.

Referring to Fig. 1 of the drawings, a 75 multiplex transmission system has been shown in which several channels 1, 2, and 3 are connected to the same antenna-ground system indicated by reference characters 4 and 5. Inductances 6, 7 and 8 are included 80 in the antenna-ground circuit 4, 5 to which the several transmission channels 1, 2 and 3 are inductively coupled.

The transmission channel indicated by 85 reference character 1 has been illustrated diagrammatically as including a generator of sustained oscillations O, a modulator M operated from a suitable modulation circuit represented by reference characters 9 and 10, and a power amplifier P for increasing 90 the amplitude of the modulated signals impressed upon the tuned circuit 11, 12 connected in series with the inductive means 14 which relates to transmission channel 1 to inductance 6 in the antenna-ground system 95 4, 5.

The transmission channels 2, and 3 may 100 contain substantially similar circuit arrangements as described in connection with transmission channel 1. The transmission channel 2 includes tuned circuit 15, 16 connected in series with the inductive means 17 which couples channel 2 with inductance 7 in the antenna-ground system 4, 5. The channel 3 may include tuned circuit 18, 19 105 connected in series with inductive means 20

which is coupled with inductance 8 in the antenna-ground circuit 4, 5.

The antenna circuit includes a plurality of branch circuits 21, 22 and 23. Circuit 21 including variable capacity 24 is tuned in combination with the antenna-ground circuit 4, 5 to the frequency of channel 3. The loop-resonant circuits 25 and 26, in branches 22 and 23 respectively, are each tuned to the frequency of channel 3 and therefore effectively remove branches 22 and 23 with respect to that frequency, that is, these branches do not affect the tuning of the antenna system so that frequency as determined by the constants of branch 21 and the antenna-ground circuit. The branch 22 is tuned in combination with the branch 21 and the antenna-ground circuit to the frequency of channel 2. This tuning is effected by variable condenser 27. The loop-resonant circuit 28 in branch 23 is tuned to the frequency of channel 2 and therefore effectively removes branch 23 with respect to that frequency in the manner above described with reference to loop-resonant circuits 25 and 26. The branch 23 is tuned in combination with branches 21 and 22 and the antenna-ground circuit to the frequency of channel 1. This is accomplished by variable condenser 29. The antenna system accordingly is given 3 degrees of freedom corresponding to the respective frequencies of the three transmitting channels.

In describing the tuning means for the various combinations, that is, the variable condensers 24, 27 and 29, it was assumed that the frequencies of the three channels decreased from channel 3 to channel 1. It is obvious that the allocation of the respective frequencies to the various combinations could be made otherwise by the use of inductances instead of or in combination with said condensers. If both inductances and condensers are used, they may be connected in series or in parallel. In a similar manner, provision can be made for any desired number of channels. For example, for four channels, a fourth branch would be added, which would contain a loop-resonant circuit tuned to each of the other three frequencies and a means for tuning the branch, in combination with the remaining branches and the antenna-ground circuit, to the fourth frequency.

In order to prevent reaction of one transmission channel upon another, I provide shunt paths in each of the transmission channels offering low impedance to the frequencies produced by the other transmission channels. That is to say, in transmission channel 1 I provide shunt paths 33 and 34 including respectively inductance 35 shunted by capacity 36 in series with capacity 37 and an inductance 38 shunted by capacity 39 in series with capacity 40. In these paths

the two loop-resonant circuits constituted by the elements 35, 36, 38 and 39 are each tuned to the frequency of channel 1. The paths therefore offer high impedance to the frequency emitted by transmission channel 1. 70 The two paths are tuned respectively to the frequencies of channels 2 and 3 by variable condensers 37 and 40 and therefore together offer low impedance to frequencies emitted by both of said channels, preventing the 75 passage of undesired currents into the transmitting apparatus connected with transmission channel 1.

The transmission channel 2 is provided with a shunt path 41 including variable 80 capacities 42 and 43 and inductances 44 and 45. If it be assumed that the frequencies of channels 1 and 3 are equally spaced from the frequency of channel 2 and the groups of elements 42, 45 and 43, 44 are tuned respectively to the frequencies of channels 1 and 3 the loop-resonant circuit constituted by all four elements will be tuned to the frequency of channel 2, accordingly path 41 has a high impedance to currents of the frequency employed by channels 2 and a low impedance to undesired currents which may have a tendency to react upon the channel 2 from channels 1 and 3. 90

Transmission channel 3 is similar to channel 1, it contains shunt paths 46 and 47 including inductance 48 shunted by capacity 49 in series with inductance 50 and capacity 51, and inductance 52 shunted by capacity 53 in series with inductance 54 and capacity 55 respectively, the said shunt paths offering high impedance to the signaling frequency in channel 3 but low impedance to interfering currents which may react upon channel 3 from channels 1 and 2. 95

Fig. 2 shows the diagrammatic arrangement of a plurality of duplex communication channels operating upon the same antenna system. Three channels have been shown at 61, 62 and 63, each including circuits for screening each channel against interference from adjacent channels while permitting transmission and reception of energy in the particular channel in which the screening means may be located. The channel 61 is divided into a transmitting circuit 64 and a receiving circuit 65. The transmission system connected to the transmission circuit 64 may include a source of sustained oscillations designated at C connected 110 to impress energy of constant frequency upon a modulation circuit including electron tube 66. The high frequency oscillations from the generator C may be modulated at voice frequency from a circuit represented at 67 and the modulated high frequency oscillations impressed upon the amplification system 68 operating to increase the amplitude of the transmitting energy and deliver the energy to the radiating antenna system 115 120 125 130

comprising antenna 56, inductance 69, capacity 70 and ground 71. Circuits *a* and *b* consisting of inductance 72 shunted by capacity 73, and inductance 74 shunted by capacity 75, are provided in the antenna connection for the purpose of screening the communication channel from reaction or disturbances of oscillations produced in adjacent channels as will be hereinafter described. The receiving system of channel 61 includes a circuit consisting of inductance 76 and shunt capacity 77, which is closely resonant to the frequency of the oscillator C of the transmitting circuit 64 but can be detuned from that frequency sufficiently to permit a desired amount of energy from the local transmitting channel to flow in the receiving circuit. This energy is used in cooperation with the incoming signal energy for the production of a beat note, enabling the signals to be observed. The receiving circuit 65 includes the primary antenna inductance 78 and tuning condenser 79 connected to ground 80. The frequency derived from the interaction of the incoming signal energy with the energy from the local source of oscillations may be impressed upon detector tube 81' and the resultant beat frequency again impressed upon a detector circuit including tube 82' to finally reproduce the signal transmitted from the distant station.

The second duplex channel represented by connection 62 with the antenna 56 has circuits *a* and *c* interposed between the transmitting and receiving apparatus and the antenna system. These circuits *a* and *c* include inductances 81 and 82 shunted by condensers 83 and 84 respectively, the circuits operating to eliminate the passage of undesired disturbances or reactions from the associated channels into the transmitting or receiving apparatus of the channel 62. The transmitter for this channel is represented as having a source of sustained oscillations indicated at B connected with suitable modulation and amplification circuits represented generally at 85, the transmitter being modulated at voice frequencies through circuit 86. The transmitting energy is delivered to the antenna system through inductance 87 connected in the antenna and ground circuit in series with condenser 86. In the lead from the antenna 56 through connection 62 to the receiving apparatus in this channel there is interposed a circuit including an inductance 89 shunted by condenser 90 tuned to exclude the frequency of the local source of oscillations B in its associated transmitter circuit. The received energy is impressed upon the receiving circuit through primary inductance 91 shunted by tuning condenser 92. A local source of oscillations may be supplied by means of a local generator 93 coupled with the secondary winding 94 through an inductance 95.

An electron tube 95' is connected to function as a detector to reduce the incoming signals to a beat note at an intermediate frequency determined by the frequency of the source 93 capable of being efficiently amplified through amplifier 96 and selectively impressed upon another detector circuit including tube 97 through a series of selective circuits 98 delivering the received energy to operate a suitable responsive device indicated at 99. The frequency of source 93 is fixed by the desired intermediate frequency which should be different from that resulting from combination of the incoming frequency with the locally transmitted and other interfering frequencies.

Channel 63 is connected with the antenna 56 with circuits *c* and *b* interposed therein for excluding interference from the associated channels. The circuits *c* and *b* comprise inductances 100 and 101 shunted by condensers 102 and 103 respectively, serving to exclude reactions from the local sources of oscillation in the transmitter circuits of the closely adjacent channels. The transmitter in channel 63 may be provided with a local generator of oscillations designated as having a frequency A, the energy from which modulated by a signal in the manner described with reference to transmitting channel 64 is impressed on the antenna circuit to inductance 104. The receiving system for the channel 63 includes a circuit in series therewith comprising inductance 105 and condenser 106 functioning to exclude undesired interference in the receiving system from the locally generated oscillations in the transmitter circuit. It may function as in channel 61 to permit a desired amount of the locally transmitted energy to flow to the receiving circuit. The receiver may be coupled to the system by primary winding 107 and secondary winding 108.

It will be observed that means are provided in each of the several channels for suppressing reactions and interference from currents occurring simultaneously in the other channels. That is to say, circuits *a* and *b* in channel 61 will suppress undesired oscillations or currents which might be impressed upon channel 61 by channel 62 or 63. The circuit 76, 77 in the receiving portion of channel 61 suppresses from the receiving circuit all except a desired amount of energy derived from the local oscillator C of the transmitter in the same channel which may be utilized in reception. In channel 62 the circuits *a* and *c* suppress undesired currents which may be developed by channel 61 or 63. The circuit 89, 90 in channel 62 prevents undesired reaction of the sustained wave from generator B of the transmitter portion of the channel from impressing itself upon the receiving portion of the channel. In channel 63 the circuits *c* and *b* sup-

press undesired currents occurring in channels 61 and 62 while the circuit 105 and 106 in the receiving portion of the channel operates to prevent undesired reaction of the sustained wave of generator A of the adjacent transmitter. All of these channels may therefore function in duplex operation in multiplex signaling on the same antenna 56 without mutual reaction or cross-talk.

10 The incoming signaling energy in the antenna system 56 distributes to the several receiving channels without interference, these being respectively selective to their individual message waves as explained in the case 15 of Fig. 1. For the purpose of clearly explaining the operation of the system, the transmitting frequency in duplex channel 61 may be assumed to have a value equal to f_1^1 . The incoming signaling energy in antenna 20 56 selected by channel 61 may have a frequency f_2^1 . A portion of the transmitting frequency f_1^1 being effectively utilized in the receiving portion of channel 61 as a local 25 source of oscillations reacts with the frequency f_2^1 from which is derived a beat note of a frequency $f_1^1 - f_2^1 = f_3^1$ which is rectified and observed. In like manner channel 62 may have a local source of transmitting 30 energy of a frequency f_1^1 , and the incoming signaling energy in antenna 56 for this channel may be f_2^1 . If desired, the frequency f_1^1 may not be used as a local source 35 in the receiving channel but instead a local generator of a frequency f_4^1 may be employed. The beat frequency thus derived will be

$$f_4^1 - f_2^1 = f_3^1$$

which may be further rectified to enable the signals to be observed.

40 Similarly the channel 63 may have a transmitting portion of frequency f_1^{11} and the incoming frequency in antenna 56 for this channel may be f_2^{11} . A portion of the transmitting frequency f_1^{11} may be utilized as a local source so that the beat frequency for the receiver will be

$$f_1^{11} - f_2^{11} = f_3^{11}$$

45 The beat frequency f_3^{11} may be further detected and the signal indicated.

50 While I have described the invention in certain particular embodiments, I desire that it be understood that modifications may be made and I intend no limitations upon the 55 invention other than are imposed by the scope of the appended claims.

What I claim is:

1. A transmitting channel comprising a 60 transmitting conductor, a circuit associated in energy transfer relation thereto, and a reactive circuit in shunt to said circuit, said reactive circuit comprising a combination of impedance elements which is loop-resonant at a frequency to be transmitted, and said reactive circuit, as measured between its ter-

minals connected to said first mentioned circuit, being also resonant at at least one frequency to be excluded.

2. A transmitting channel comprising a 70 transmitting conductor, a circuit associated in energy transfer relation thereto, and a reactive circuit in shunt to said circuit, said reactive circuit comprising a combination of impedance elements which is loop-resonant at a frequency to be transmitted, and said 75 reactive circuit, as measured between its terminals connected to said first mentioned circuit, being series-resonant at a plurality of frequencies to be excluded.

3. A multi-tuned antenna system comprising, in combination, a grounded aerial and a plurality of grounded circuits, corresponding to the number of frequencies to which it is desired to tune the system as a whole, connected in parallel with each other and with said grounded aerial portion; means in one parallel circuit which combines with said grounded aerial portion to tune the system to one desired frequency, anti-resonant means in each of the other parallel circuits to effectively isolate them from the grounded portion and the first parallel circuit at said other desired frequencies, means in a second parallel circuit which combines with the grounded aerial portion and the first parallel circuit to tune the system to a second desired frequency, anti-resonant means in each of the parallel circuits, exclusive of the first and second, to effectively isolate them from the grounded aerial portion and the 95 first and second parallel circuits, as to the first and second desired frequencies; and similarly for each of the other desired frequencies.

4. A multiplex radio transmitting circuit 105 comprising a plurality of sources of transmitting waves of respectively different frequency, individual transmission circuits associated with each source, each such circuit having connected across it as many shunt 110 circuits as there are other transmitting circuits, each shunt circuit being tuned to be anti-resonant at the frequency of the waves from the source connected to that transmission circuit, each of said shunt circuits 115 being series resonant at the frequency of a different respective one of the other wave sources, and an antenna connected in common to all of said transmitting circuits and having a plurality of degrees of freedom corresponding in frequency to the individual frequencies of each of said transmission circuits.

5. A system as defined in claim 4 in which 125 each of said transmission circuits includes means for making the circuit series resonant at the frequency of the waves transmitted by it.

6. A multi-tuned antenna system comprising, in combination, a grounded aerial and 130

a plurality of grounded branches, means to tune the grounded aerial circuit to one of the operating frequencies, anti-resonant circuits in each of a plurality of said branches
5 for effectively isolating them from said aerial circuit at said operating frequency, means in one of said branches which combines with said first tuning means to tune the system to a second operating frequency,
10 an anti-resonant circuit in another of said branches for effectively isolating it from said aerial circuit at said second operating frequency, and means in said last-mentioned branch which combines with the grounded aerial portion and the other branch to tune 15 the system to a third operating frequency.

In witness whereof, I hereunto subscribe my name this 15th day of May A. D., 1924.

RAYMOND A. HEISING.
